UNITED STATES PATENT OFFICE.

PRINCE EDWARD WHITE, OF PERTH AMBOY, NEW JERSEY.

MECHANICAL HANDSAW.

1,110,363.

Specification of Letters Patent. Patented Sept. 15, 1914.

Application filed November 19, 1913. Serial No. 801,781.

To all whom it may concern:

Be it known that I, PRINCE E. WHITE, a subject of the King of Great Britain, and residing at Perth Amboy, in the county of Middlesex and State of New Jersey, have invented certain new and useful Improvements in Mechanical Handsaws, of which the following is a specification, such as will enable those skilled in the art 10 to which it appertains to make and use the same.

This invention relates to hand saws for use in work shops of various kinds and classes, and the object thereof is to provide 15 an improved device of this class which may be operated by compressed air or other power medium, or by hand, and with this and other objects in view, the invention consists in a device of the class specified 20 constructed as hereinafter described and claimed.

The invention is fully disclosed in the following specification of which the accompanying drawing forms a part, in which the 25 separate parts of my improvement are designated by suitable reference characters in each of the views, and in which;—

Figure 1 is a side view of my improved saw; Fig. 2 a central longitudinal section; 30 Fig. 3 a section on the line 3—3 of Fig. 2, and on an enlarged scale; Fig. 4 a section on the line 4—4 of Fig. 1, and on an enlarged scale, and; Fig. 5 a transverse section on the line 5—5 of Fig. 2, and showing a modification and being also on an enlarged scale.

In the practice of my invention, I provide an oblong frame a composed of parallel side members a^2 and a^3 which, for the purpose 40 of this description, will be called front and back side members, and said side members are connected at the front and rear ends a^4 and a^5 in any desired manner.

The back side member a^3 is provided with 45 a longitudinally movable slide b to the front end portion of which is secured a saw c , this connection being preferably made by means of screws c^2 having thumb nuts c^3 , said screws being passed through the saw 50 into the slide, but my invention is not limited to any particular means for connecting the saw c with the slide b , and this connection may be made in any desired manner. The part a^3 of the frame is provided with 55 a groove d which is T-shaped in cross section and which extends through the part a^3

at one portion of the same, to form a slot d^2 . The slide b which is shaped similar to the groove d is mounted in said groove, as shown in Fig. 2. This form of slide and its mounting forms an inexpensive construction, in that only one piece of material is necessary for each part and at the same time it provides a structure in which the saw will be guided as accurately as it is possible to direct a saw. Another desirable feature of the slide and mounting is that the parts may be quickly and easily assembled or taken down and simply lubricated. Mounted transversely in the front side portion a^2 60 of the frame, and forwardly of the middle thereof, in the construction shown, is a shaft e on the inner end of which is mounted and secured a wheel f with which is connected at f^2 a crank rod g , which is connected with the slide b at g^2 , said crank rod being provided with a stud g^3 movable in that part d^2 of the groove d which opens inwardly. The front side a^2 of the frame is provided with a circular housing h 65 through which the shaft e passes, and said shaft e is provided within said housing with a bucket wheel i having radial blades i^2 forming buckets i^3 , and the housing h is provided on the rear side thereof with a coupling extension h^2 having a bore h^3 and with which is connected a pipe or pipe coupling j with which, in practice, is connected a flexible pipe j^2 through which air under 70 pressure is applied to the housing h . The front end of the frame is provided with a forwardly directed bearing k in which is mounted a transverse shaft k^2 having a spur wheel k^3 , and the shaft k^2 or the ends thereof are movable forwardly and backwardly 75 in the bearing k , and rearwardly of said ends of said shaft are placed spiral springs k^4 which normally hold the spur wheel k^3 in its projected position, and at the back side of the bearing k is secured a blade m 80 100 in the front end of which is provided with teeth m^2 .

The shaft e is preferably provided at n with ball bearings, and the operation of this form of construction will be readily 105 understood from the foregoing description when taken in connection with the accompanying drawing and the following statement.

In Figs. 1 and 2, I have shown at o a work 110 piece, and in the normal position of the wheel k^3 , it projects beyond the plate, or the

teeth of the plate m , and in the beginning of the use of the saw, the teeth m^2 of the plate m are pressed against the work piece so as to facilitate the exact placing of the saw on 5 said work piece, which has been previously marked for this purpose. This operation forces the wheel k^3 backwardly and when the saw has been put in operation, pressure on the frame is removed and only the wheel 10 k^3 or the teeth thereof bear on the work piece, and this facilitates the movement of the saw across the work piece either vertically, or in any other direction that may be desired. With the construction shown in 15 Figs. 1, 2 and 3, air under pressure enters through the pipe j^2 and operates the wheel i , as will be readily understood, and the wheel i operates the shaft e which in turn operates the wheel f , and the saw c is operated by the 20 crank rod g . The housing h is provided with an exhaust port p which is preferably located in the back bottom portion thereof and connected therewith is a curved pipe p^2 by 25 which the exhaust air from the housing h may be used for the purpose of blowing away sawdust from the work piece.

In Fig. 5 of the accompanying drawing, I have shown a modification in which the means for operating the saw by compressed 30 air including the housing h is omitted, and the shaft e is provided in the front side a^2 of the frame with ball bearings n , and said shaft is also provided with a crank r by 35 which it may be operated, and with this construction, the saw may be operated by hand, as will be readily understood.

The frame a is provided at the rear side thereof, and at or near the front end thereof with a guide within which the saw works, 40 and which is intended to prevent the buckling or breaking of said saw, and said frame is also provided, preferably on the back side thereof and near the rear end thereof, with a handle t which is secured thereto longitudinally 45 thereof, and by means of which the device may be held and controlled in the operation thereof, and other handles may be provided if desired, and the wheel f and crank rod g may also be covered by hoods 50 connected with the top and bottom of the frame if desired, and while I have described the preferred form of my improvement as operated by air, it will be understood that other power mediums may be employed, and 55 changes in and modifications of the construction herein described may be made, within the scope of the appended claims, without departing from the spirit of my invention or sacrificing its advantages. My invention is

also not limited to the use of a blade saw, 60 as shown, and any kind of a saw may be connected with the slide b .

Having fully described my invention, what I claim as new and desire to secure by Letters Patent is:—

1. In a hand saw device, a frame, a wheel mounted therein, means for turning said wheel, a slide mounted in said frame and operated by said wheel, and a saw connected with said slide and adapted to be projected 70 beyond one end of the frame, said end of the frame being also provided with a spur wheel having spring projected bearings and at one side of which is a toothed blade beyond which the wheel is normally projected.

2. A mechanical saw comprising an oblong frame composed of parallel side members, one side member of said frame being provided with a housing, a shaft mounted in said housing and extending into said frame, 80 a wheel mounted on the said shaft between the side members of the frame, a guide way provided on the other side member, a slot placing said guide way in communication with the inside of the frame, a slide mounted in said guide way, a link provided in said frame and having a part which extends through said slot and is connected to said slide, the link being also connected to the wheel, a saw detachably connected with one 90 end of said slide, and means for operating said shaft.

3. A mechanical saw comprising an oblong frame composed of parallel side members, one side member of said frame being provided with a housing, a shaft mounted in said housing and extending into said frame, a wheel mounted on the said shaft between the side members of the frame, a T-shaped guide way provided on the opposite side member, a slot placing said guide way in communication with the inside of the frame, a T-shaped slide mounted in said guide way, a link provided in said frame and having a part which extends through said slot and is connected to said slide, the link being also connected to the wheel, a saw detachably connected to said slide, and means for operating said shaft.

In testimony that I claim the foregoing 110 as my invention I have signed my name in presence of the subscribing witnesses this fifteenth day of November 1913.

PRINCE EDWARD WHITE.
